[57] CLAIM

The ornamental design for a belt buckle cover, as shown.

DESCRIPTION

FIG. 1 is a front elevational view of a belt buckle cover showing my new design;

FIG. 2 is a bottom plan view thereof;

FIG. 3 is a top plan view thereof;

FIG. 4 is a rear elevational view thereof;

FIG. 5 is a right side elevational view thereof;

FIG. 6 is a left side elevational view thereof;

FIG. 7 is a front elevational view of a belt buckle cover showing a second embodiment of my new design;

FIG. 8 is a bottom plan view of FIG. 7;

FIG. 9 is a top plan view of FIG. 7;

FIG. 10 is a rear elevational view of FIG. 7;

FIG. 11 is a right side elevational view of FIG. 7;

FIG. 12 is a left side elevational view of FIG. 7; and,

FIG. 13 is a perspective view of FIG. 7.

The broken line showing of a belt buckle, in FIGS. 1, 2, 3, 5, 6, 7, 8, 9, 11, 12 and 13, is for illustrative purposes only and forms no part of the claimed design.
